UNITED STATES PATENT OFFICE.

JOHN PRESSLEY COLEMAN, OF EDGEWOOD, PENNSYLVANIA, ASSIGNOR TO THE UNION SWITCH AND SIGNAL COMPANY, OF SWISSVALE, PENNSYLVANIA, A CORPORATION OF PENNSYLVANIA.

CLIP FOR DETECTOR-BARS.

SPECIFICATION forming part of Letters Patent No. 724,439, dated April 7, 1903.

Application filed January 10, 1903. Serial No. 138,527. (No model.)

To all whom it may concern:

Be it known that I, JOHN PRESSLEY COLEMAN, a citizen of the United States, residing at Edgewood, in the county of Allegheny and 5 State of Pennsylvania, have invented certain new and useful Improvements in Clips for Detector-Bars, of which the following is a specification.

My invention relates to clips or brackets 10 which are employed to support detector-bars in position alongside a railroad-rail.

I will describe a clip or bracket embodying 15 my invention, together with several modifications, and then point out the novel features thereof in the claims.

In the accompanying drawings, Figure 1 is 20 a top plan view of a clip embodying my invention, a part of a railroad-rail, and a part of a detector-bar. Fig. 2 is a view, partly in vertical transverse section and partly in elevation, of the clip shown in Fig. 1. Figs. 3 and 4 are each detail views. Fig. 5 is a side elevation of a modified form of clip embodying 25 my invention. Fig. 6 is a view, partly in elevation and partly in vertical section, of the clip shown in Fig. 5 and drawn to a larger scale. Fig. 7 is a view similar to Fig. 6, but showing another modification. Fig. 8 is a detail view of a part of the clip shown in Fig. 7.

Similar letters of reference designate corresponding parts in all of the figures.

A designates a portion of a railroad-rail.

B designates a portion of a detector-bar, and 30 b one of a number of motion-plates which is suitably secured to the detector-bar.

b' designates a cam, here shown as being in the form of a rib, provided on the motion-plate, with which the clip coacts to give the desired motion to the detector-bar when the 40 detector-bar is moved longitudinally by any desired mechanism. If desired, the cam b' may be formed directly on the detector-bar.

C designates a clip or bracket, and D a clamp for securing the clip or bracket to the 45 rail. The clip is here shown as comprising two independent parts c c'. The part c is so formed as to fit under the head and on top of the flange on one side of the rail, and it is provided with a step c². The part c' is provided with a lug or projection c³, which coacts

with the cam b' in the usual manner, and its lower end rests on the step c² of the part c, which is provided for it. The two parts in the form shown in Figs. 1 and 2 are secured together by means of a bolt c⁴, the head of 55 the bolt fitting in a countersunk recess provided in the part c. The two parts are suitably spaced apart by a cylindrical portion c⁵, integral with the bolt and of a greater diameter than the shank of the bolt. The bolt 60 is retained in the two parts by means of a pin c⁶.

c⁷ designates a roller journaled on the cylindrical portion c⁵, and it serves as an anti-friction-surface on which the cam b' travels. 65

The clamp D is here shown as being in one piece and as having a rib d, which is provided to strengthen the clamp. The clamp is provided with a flat surface portion d', which fits the bottom of the rail-flange, and 70 with a hook portion d' at one end, which receives an edge portion of the rail-flange. The opposite end of the clamp is provided with an upwardly-inclined portion, which assists in supporting the clip C. The rib d beneath 75 this inclined portion is of considerable depth, as the greatest strain from the clip and detector-bar is put upon the clamp at this point. The clamp is also provided with a boss d³ at this end, in which a bolt d⁴ works. This 80 bolt is provided to hold the clip C in position on the rail, and, as shown in Figs. 1 and 2, the bolt d⁴ acts directly on the head of the bolt c⁴. A locking-nut d⁵ is provided on the bolt d⁴ to hold it in any adjusted position. 85

In Figs. 4 and 5 the two parts c c' of the clip are spaced apart by a washer e, which surrounds the bolt c⁴, and instead of a pin for holding the bolt c⁴ a nut e' is employed. In this form also the clamp D does not directly assist in supporting the clip, but instead the bolt d⁴ is placed in such position in the clamp as to assist in supporting the clip. In this form the end of the bolt d⁴ fits in a recess or socket provided in the lower 90 portion of the part c'.

In Figs. 7 and 8 I employ the same means for connecting and spacing the two parts of the clip illustrated in Figs. 5 and 6 and the same form of clamp shown in Figs. 1 to 4. 100

What I claim as my invention is—

1. The combination with a clip for a detector-bar, of a clamp independent of the clip for holding the clip in position on a railroad-rail, said clamp being in one piece, extending under the flange of the railroad-rail, having a hook at one end to receive an edge portion of the flange of the railroad-rail and a clamping-bolt which engages the clip.
2. The combination with a clip for detector-bars, of a clamp, independent of the clip, for holding the clip in position on a railroad-rail, said clamp being in one piece, extending un-

der the flange of the railroad-rail, having a hook at one end to receive an edge portion of the flange of the railroad-rail, having a portion which assists in supporting the clip and a clamping-bolt which engages the clip. 15

In testimony whereof I have signed my name to this specification in the presence of 20 two subscribing witnesses.

JOHN PRESSLEY COLEMAN.
